ATTACHMENT FOR ELECTRICAL FRE-
QUENCY SHIFTERS

Harry R. Clark, Brooklyn, N. Y.

Application April 15, 1937, Serial No. 136,971

3 Claims. (Cl. 200—11)

This invention relates to electrical frequency shifters and more particularly to an attachment therefor.

The object of the invention is to provide such an attachment so that by a very simple manipulation it is possible for a user of a radio apparatus or the like, to obtain the station desired. The improvement lends itself also to remote control.

10 The invention consists in providing elongated recesses on a surface member, disposed in continuation in relation to a series of impediments, with each elongated recess corresponding to a group of 10's, and in providing non-elongated recesses on said surface member, one for each unit in the 10's, also adapted to be engaged by impediments, these impediments being operated by members corresponding to the 10's desired and by members corresponding to the units desired, the impediments of the units being arranged in staggered relation to the members of the 10's, whereby combinations of 10's and units may be made from a desired minimum to a desired maximum of units by engaging one of the 10's impediments to result in the desired ten unit and for unital portions, in addition to said ten unit, if desired, by operating the corresponding impediment member for the unit on the surface member.

15 The embodiment shown consists of a rotary disc having such elongated recesses and non-elongated recesses, with a plate member disposed diametrically to the disc, and upon the plate member are push buttons or the like arranged in two series, one series for the 10's, and one series for the units, and these 10 series and unit series are arranged in staggered relation with each other, and in relation to the disc.

20 Assuming a disc provided with kilocycle demarcations ranging from 500 to 1500 and subdivided into units of 10's corresponding to each channel now permitted under the present regulations, the elongated recesses provided upon the disc correspond to each group of ten subdivisions upon the peripheral portion of the disc, and the multiplicity of non-elongated recesses correspond to each unit subdivision upon the peripheral portion of the disc. The push button members are arranged in electrical circuit connections so that the pressing down of the member causes the disc to rotate and to continue to rotate until the desired station is obtained, when the rotating ceases.

25 Another embodiment of my invention contem-

plates the use of the device just described, in connection with remote control.

Finally, the embodiment of the invention described is suitably connected with means whereby indications of a red lamp or a green lamp are utilized with the cutting out of the dynamic speaker, and also provision is made for the reversal of the direction of rotation of the disc of the embodiment described.

30 The invention will be described hereinafter and embodiments thereof shown in the drawings, and the invention will be finally pointed out in the claims.

In the accompanying drawings:

35 Figure 1 is a front view of one embodiment of my invention, showing the same connected with an electric motor for rotating the disc,

Figure 2 is a plan view of Figure 1,

40 Figure 3 is a detailed enlarged sectional view taken on line 3—3 of Figure 1 of a portion of the disc and of the push button members cooperating therewith, showing at the same time the remote control provision for these push button members, and showing in section the recesses for the tens and the units, and

45 Figure 4 is a diagrammatic view of the embodiment shown in Figure 1, with the electrical parts in diagrammatic form.

50 Similar characters of reference indicate corresponding parts throughout the various views.

Referring to the drawings, and more particularly to Figure 1, the disc 10 is of a suitable diameter and of a thickness in correspondence therewith as generally shown in Figures 1 and 2. The axis of the disc is shown at 11. The disc is 55 rotated by having a pulley 12 in turn rotated by the motor 13, the pulley 12 having its peripheral contact with the periphery of the disc 10.

Upon the upper half of the disc 10 there is arranged a band extending 180° around the periphery of the disc. This band 14 is subdivided into 150 subdivisions 15. The beginning of this band is marked with "500", corresponding to 500 kilocycles, and after ten subdivisions 15 are provided, the tenth subdivision line 15 is indicated by the number "600", corresponding to 600 kilocycles, and so on, until "1500" has been obtained. If desired, the intermediate subdivision corresponding to the "50" can be indicated, as for instance, "750" and "1250", corresponding to the kilocycles.

55 Upon the face of the disc 10 there are arranged a plurality of elongated recesses 17, each of which corresponds to ten subdivisions. That is, when the disc 10 rotates in respect to a stationary point, the arm and movement will correspond

to ten subdivisions. As this stationary point may vary in its radial position in respect to the disc, there are necessarily variations in the length of these elongated recesses. The disc 10 is also provided with a plurality of non-elongated recesses, preferably circular in form, these being indicated by 18. Preferably, the disc is of an electrical conducting material, such as metal, or any other substance suitable for manufacturing purposes, and these elongated recesses 17 and non-elongated recesses 18, may be arranged in the disc in suitable position by providing suitable recesses in the material of the disc 10 and placing into such recesses members of insulating material which in turn have either the elongated recesses or the non-elongated recesses.

For instance, in Figure 3 the disc 10 is provided with the recess 19, and into this recess there is placed the insulated member 20 having the curved and circular recess 18. The members 17 are constructed in substantially the same manner as the member 20, excepting that they are somewhat circular in form, as seen from Figure 1, and, as stated, have elongated recesses.

The axis 11 of the disc 10 is supported by sleeve member 22 which is engaged to an upright 23 suitably secured to some part of the radio apparatus by means of bolts 24. This sleeve 22 passes through an insulated member 24 and extends to the front of the disc 10 where it supports a vertical plate 25. This vertical plate is preferably made of insulated material, as shown in Figure 3, and has a plurality of openings therein. There are eleven openings on the left-hand side of the plate 25, and ten openings on the right-hand side of the plate 25. It will be noted that these two series of openings are arranged in staggered relation with each other. Each of these openings is provided with a bushing 26 of electrical conducting material, and through these bushings pass stems 27 of push button switches. These stems 27 are provided with a shoulder 28, and there is a spring 29 disposed between the bushing 26 and the shoulder 28. The stems 27 are provided with an insulated button 30. The other end of the stems 27 has an electrical contact member 31 preferably made of a plate having its two free ends joined together, each having a hole adapted to be brought into registration with the other hole and with a screw 32 passing through the holes to secure these ends to the stem 27. The plate 31 has a teat-like projection 32 adapted to fit into the recess 18 of the non-elongated recesses or into the elongated recesses 17. The bushings 26 are connected by a metal band 34 to wires 35 and 36, as shown in Figure 3.

All of the bushings on the left-hand side of the plate 25 are connected together by this wire 35, and all of the bushings on the right-hand side of the plate 25 are connected together by the wire 36, and the wire or conductor 36 is connected with the conductor 35 by the conductor 37, and the conductor 35 is then connected with a conductor 38 going to one potential of the circuit. The other potential of the circuit is connected with a conductor 39 to one terminal 40 of the motor 13, the other terminal 41 of the motor being connected with a conductor 43 to a contact member 44 which engages the peripheral portion of the disc 10 made of suitable conducting material to permit current to pass therethrough.

The push button members 30 upon the plate

25, as shown in Figure 1, are marked on the front thereof with certain numbers, the left-hand group or numbers 5 to 15, corresponding to the 500 kilocycles and 1500 kilocycles on the peripheral band 14 of the disc 10. The group of push buttons on the right-hand side of the plate 25 are each marked 10, 20, 30, 40, 50, 60, 70, 80, 90, and 00, corresponding to the subdivisions in the peripheral band 14 of the disc 10. If then, it would be desired to have the station known as 10 710, the button marked 7, and the button marked 10 would be pressed, and the device would be set into operation until the station 710 has been obtained. With the position of the parts as shown in Figure 1, if the buttons "7" and "10" be pressed, the electric circuit 35, 38, 39, 40, 41, 43, 44 and 10 will be immediately closed and the motor will be set into operation so as to rotate the disc 10. When the disc has been rotated so as to bring the corresponding elongated recess 17 into registration with the switch point 32, the circuit will become broken on account of the insulation forming the elongated recess 17. But as the switch member 32 which has been pressed down by pressing the button 10 causes the circuit to be closed, the disc will continue to rotate until the switch member 32 engages into that corresponding non-elongated recess 18. When it does so engage, the circuit has been broken and the motor ceases to rotate. The motor used is, of course, one which starts quickly and stops with the breaking of the current.

For remote control, it is merely necessary to provide a duplicate of plate 25, and upon this duplicate plate, not shown, there are provided a plurality of solenoids 45, one for each push button member. A third plate, having a series of push button switches thereon, would be also provided near the place of comfort of the listener. Such a plate is shown in Figure 3 and indicated by 46, the push button being indicated by 47. An electric circuit is provided in which the push button 47 is indicated, this circuit consisting of the conductor 48 connected with one potential and conductor 49 connected with the other potential, this conductor 49 passing around the coil of the solenoid and being adapted to have its circuit closed by the push button 47 contacting with the point 50 of the conductor 49. The solenoid has the well known armature 51. Thus by a user having a plate with a corresponding series of push buttons thereon, he need simply press the desired push buttons and set the solenoids into operation supported by the duplicate plate, and the solenoids being in registration with the push buttons shown in Figures 3 and 1, the push buttons 30 will be moved to a position so as to check rotation of the disc 10.

For the purpose of returning the disc 10 to its initial position, a reversing switch is provided which is shown in dotted lines in Figure 1, and which is shown in electrical diagram form in Figure 4. This switch is the ordinary lever type having its axis arranged coaxially with the axis 11 of the disc 10. The handle 55 of this switch is moved in one or the other position as shown in Figure 4 either in the full line position or in the dotted line position. In the full line position, the contact member 56 of this switch 57 makes contact with the conductor 58 which is connected with the conductor 43. This conductor 58 in turn is connected with a conductor 59 which is connected with one brush 60 of the motor, the other brush 61 being connected with the conductor 62 contacting with the conductor 75

63 which is connected in turn with the conductor 39 whereby the circuit is closed. Switch 57 is moved by its arms being acted upon by either abutment 68 or 69, on the turning of the disc. 5 The handle 55 permits manual operation. The contact point 58 contacts with either the contact point 58 or 64 and closes the respective electric circuits.

Thus, by the operation of the reversing switch 10 57, the motor is operated in either one or the other direction, the operation of the reversing switch and its electrical connection being well-known and not claimed herein.

In addition to the parts described, there is 15 shown in Figure 4 a diagram having the conductors 70 and 71 leading to the low voltage pilot light supplied from the filament winding and having a red light 72 and a green light 73, a switch 75 is provided and conductors 76 and 77 20 lead to the output winding of the set. Dynamic speaker 79 is shown as in circuit. The conductors 80 and 81 are respectively connected with the conductors 39 and 43. These electrical parts are 25 well-known and not described in detail and form part of the usual set, and are not claimed herein.

It will be seen from the foregoing that the invention is an electrical tuning mechanism whereby a radio set is tuned accurately, quickly and simply to any and all desired frequencies without 30 the usual pre-selecting or setting up of cogs, pegs, and mechanical and electrical contacts, also doing away with the limitations that usually accompany automatic tuning of the mechanical or electrical type.

35 With this invention it is possible to select any desired station according to kilocycles with the pressing of the two buttons which correspond with the desired station being tuned. It is possible to tune electrically any station without 40 pre-determination or set-ups, one hundred different stations on the broadcast band, with the combined twenty-one buttons, accurately and with a minimum amount of cost relative to mechanism and manufacture.

45 The control panel or plate 25 is placed over a movable metallic disc having insulated recesses of circular shape and elongated shape. This tuning disc is rotated by a motor which only operates when the tuning buttons are pressed.

50 The connection between motor and disc may be such as to make it possible to attach this mechanism to any type receiver without any mechanical or electrical changes in dial assembly or radio set assembly.

55 In the embodiment shown, a broadcast band of 500 to 1500 kilocycles has been shown with automatic tuning possible at every ten kilocycles, but should it be necessary to require a greater number of stations that may be out of this band of 60 frequency, or stations less than ten kilocycles apart, this can be readily accomplished with the addition of other control buttons and increased amount of selector indentations.

It will have been noted that the tuning buttons 65 are wired in parallel, making one side of a switch, whereas the metallic surface tuning disc constitutes the other pole of the switch. This means that in order to obtain contact between the two poles creating a closed circuit, it is necessary to have made contact with the tuning disc with one or more tuning buttons. The tuning buttons are mounted on the control plate of insulated material. They are mounted in such a way that their spring contacts do not make contact with the tuning disc unless pressed, and

upon released pressure they are immediately brought back to their suspended position by means of a coil spring. Upon the making of contact of said button with the tuning disc, thereby closing the circuit to the motor, the tuning disc is thereby revolved against the button contacts or impediments, and ceases to revolve only when both said contacts coincide with the two pre-arranged insulated indentations in said tuning disc. These indentations constitute the selecting elements for that particular station of selection. This operation holds true to any combination of two buttons on the control plate with corresponding numbers reading or indicating any particular station so arranged. This makes it 10 15 possible to select one of any buttons in the first column, and one of any of the buttons in the second column, and obtain any radio signals of ten kilocycles apart, or less. The relative position of the control buttons and the insulated indentations in the tuning disc, is arranged at the time of manufacture for the particular type of tuning mechanism used.

It is possible, for certain stations, to utilize 20 either one button or two buttons. Assuming the station desired to be "700", this can be obtained either by pressing button 1, corresponding to 700, or by pressing button 6, corresponding to 600, and then pressing the unit button "00", the ten units added to the six 10's, make up the 700. 25 30

In the following underlying statement of the principle, I have called the parts corresponding to the buttons "5" to "15" as 10's, and the parts corresponding to the buttons "10" to "00" as 35 units, but any other phraseology defining the relationship may be used.

It will, therefore, have been seen that elongated recesses are arranged on a surface member and disposed in continuation in relation to a series of impediments, the elongated recesses corresponding to a group of 10's. There are also non-elongated recesses on said plate, one for each unit in the 10's disposed to be engaged by a series of impediments in staggered relation to the first impediment, whereby combinations of 40 45 10's and units may be made from a desired minimum to a desired maximum of units by engaging two of the impediments corresponding to 10's to result in the desired 10 unit, and for unital operation in addition to said 10 unit, if desired, by 50 providing a corresponding impediment to the unit in the surface member.

It is, of course, clear that in order to carry out this principle of operation underlying the invention, it is not necessary to have the disc of 55 circular shape and the plate 25 of the shape as shown, since a sliding plate may be used in place of the disc, and other variations may be made within the spirit of the invention as defined by this underlying principle.

In Figure 2 is shown the support 23 for the shaft 10a of the disc, which is secured to the disc and supported in the sleeve 22. The support 23 is not shown in Figure 1. The device shown in Figure 1 may be installed in a radio apparatus during its construction, and the shaft of the disc may be coupled to the standard tuning mechanism of the radio. In such cases, where the radio is already completely manufactured, the structure of Figures 1 and 2 may be applied as an attachment to the radio. In such a case, shaft 10a may be suitably coupled to the shaft of the standard tuning dial. Or, a pulley 10b shown in dotted lines in Figure 2 may, by means of a belt, be coupled with a pulley on the condenser shaft, 70 75

not shown. Or, a gearing arrangement on the disc 10 may cooperate with a gearing on the standard tuning dial. Many other connections suggest themselves.

5 While I have illustrated and described the preferred form of construction for carrying my invention into effect, this is capable of variation and modification without departing from the spirit of the invention. I, therefore, do not wish 10 to be limited to the precise details of construction set forth, but desire to avail myself of such variations, modifications and adaptations as come within the scope of the appended claims.

What I claim is:

- 15 1. Apparatus for tuning a radio set, comprising, in combination, a metallic disc carrying thereon a plurality of arcuate, insulated major elements and also carrying thereon a plurality of insulated minor elements, a set of manually settable contact making and breaking plungers movable back and forth from the face of said disc, adapted to engage electrically with said disc, and normally in circuit-breaking position, a second set of manually settable contact making and breaking 20 plungers movable back and forth from the face of said disc, adapted to engage electrically with said disc, and normally in circuit-breaking position, the two sets of plungers being respectively adapted to cooperate with said insulated major 25 elements and said insulated minor elements, a terminal connected to said metallic disc, and another terminal connected in parallel to all of said plungers whereby the movement of at least one plunger to circuit making position closes a circuit until said 30 plunger comes into engagement with one of said insulated elements on the disc when the latter is rotated.
- 35 2. Apparatus for tuning a radio set, comprising, in combination, a metallic disc carrying thereon a plurality of arcuate, insulated major elements and also carrying thereon a plurality of insulated minor elements, a set of manually settable contact making and breaking plungers movable back and forth from the face of said disc, adapted 40

to engage electrically with said disc, and normally in circuit-breaking position, a second set of manually settable contact making and breaking plungers movable back and forth from the face of said disc, adapted to engage electrically with said disc, and normally in circuit-breaking position, the two sets of plungers being frictionally mounted and normally spring pressed away from the disc and also respectively adapted to cooperate with said insulated major elements and 10 said insulated minor elements, a terminal connected to said metallic disc, and another terminal connected in parallel to all of said plungers whereby the movement of at least one plunger to circuit making position closes a circuit until said 15 plunger comes into engagement with one of said insulated elements on the disc when the latter is rotated.

3. Apparatus for tuning a radio set, comprising, in combination, a metallic disc carrying thereon 20 a plurality of arcuate, insulated major elements and also carrying thereon a plurality of insulated minor elements, a set of manually settable contact making and breaking plungers movable back and forth from the face of said disc, adapted to 25 engage electrically with said disc, and normally in circuit-breaking position, a second set of manually settable contact making and breaking plungers movable back and forth from the face of said disc, resilient contact points mounted on 30 one end of all of said plungers and adapted to engage electrically with said disc, and normally in circuit-breaking position, the two sets of plungers being respectively adapted to cooperate with said insulated major elements and said insulated 35 minor elements, a terminal connected to said metallic disc, and another terminal connected in parallel to all of said plungers whereby the movement of at least one plunger to circuit making 40 position closes a circuit until said plunger comes into engagement with one of said insulated elements on the disc when the latter is rotated.

HARRY R. CLARK.
